UNITED STATES PATENT OFFICE.

CHARLES E. EMERY, OF BROOKLYN, NEW YORK.

TUBE-EXPANDER.

SPECIFICATION forming part of Letters Patent No. 355,644, dated January 4, 1887.

Application filed April 26, 1883. Renewed December 3, 1885. Again renewed September 23, 1886. Serial No. 214,394. (No model.)

To all whom it may concern:

Be it known that I, CHARLES E. EMERY, of the city of Brooklyn, county of Kings, and State of New York, (office New York city,) have invented certain new and useful Improvements in Tube-Expanders; and I do hereby declare that the following is a full, clear, and exact description of the same.

The invention relates to an apparatus for expanding the ends of metal tubes so as to make fluid-tight joints in flanges, couplings, or fittings of various kinds used to connect successive lengths of tubing together.

When the apparatus is used to secure a flange on the end of a tube, such flange may be bolted to a flange on the adjacent end of the next tube, in the usual way. When pipe-couplings adapted for the use of this apparatus are employed, one would be secured on one end of each tube in the first place, and then the pipes put together successively, commencing at one end, by inserting the end of a pipe not provided with a coupling into a coupling on the end of the line of pipe which is being established, and introducing into the piece of pipe last applied the apparatus to which this invention refers, and expanding the joint in a coupling by an operation conducted through the length of tube last applied.

The apparatus herein referred to is intended to be used principally in connection with my improved joints, which are adapted for this particular method of working such apparatus, making it possible to obtain fluid-tight joints without the use of screw-thread sockets, cone-rings, or other devices necessarily employed in securing the lengths of thin pipe by ordinary methods.

My invention relates, first, to an improvement in what is known as the "Dudgeon Tube Expander," with which it is possible to roll grooves in the tubes for the purpose of securing the same to couplings, flanges, &c.; second, to apparatus for use in combination with a tube-expander which enables the expander to be operated efficiently at a considerable distance within a tube from the open end thereof.

The several features of the invention will be fully set forth further on.

The accompanying drawings form a part of

this specification, and represent what I consider the best means of carrying out the invention.

Figure 1 is a central longitudinal section showing a tube in the act of being expanded into a stout ring into which the adjacent end of the next length of tube has been previously expanded. Fig. 1^a shows a small portion thereof on a larger scale. Fig. 2 is a section on the line y y, Fig. 1. Fig. 3 represents the yoke which applies as a gage against the stout coupling-ring resting on a section of the tube which is being fastened. Fig. 4 is a longitudinal section through the expander and immediately adjacent parts on a larger scale. Fig. 4^a is a corresponding section showing the completed joint after the expander is removed, with the ring in a modified form. Fig. 5 is a cross-section on the line x x in Fig. 4. The remaining ten figures represent modifications. Fig. 6 is a section corresponding to Fig. 4, there being no inner series of rollers, and with the mandrel tapered in the opposite direction. In operating this form of expander mechanism the mandrel D and the expansion-tube D' are moved by the screw G in the opposite direction to that in which they are moved in Figs. 1 and 3. This figure shows the ordinary Dudgeon rollers. Such can be used with the form shown in Figs. 1 and 4, if preferred, and some portions of the advantages of my invention can be realized by such use. Fig. 7 is a cross-section of the device shown in Fig. 6 with the ring C omitted. The remaining eight figures will be described further on.

Similar letters of reference indicate corresponding parts in all the figures.

Referring to Figs. 1, 1^a, 2, and 3, A and B are two lengths of large thin iron tubing which it is desired to strongly, rigidly, and tightly connect. It will be understood that the tube A is connected to a line which may extend for an indefinite distance, all connected together by means of my invention.

C is a stout union-ring, of cast iron or other suitable material, certain portions being denoted by additional marks, when necessary, as C' C².

C' are circular ribs formed on the outside in the planes where the expanding is effected.

C² is an internal rib extending around at the mid-length of the tube.

C² C⁴ are internal ribs, formed and arranged as shown, to take a strong hold on the tube 5 when a tube is expanded strongly into the channel c between them.

Each ring C has two of the channels c, each with the internal ribs, C³ C⁴, adjacent. The expansion is effected by hard-steel rollers, 10 caused to traverse around in the interior of the tube and to swell that portion of the metal outward on the principle employed in the well-known Dudgeon expander. Certain peculiarities of the expander itself will be described 15 further on.

D is a tapering mandrel fixed on a tube, D', and in line therewith. The tube D' is of a length somewhat greater than that of the tube, B, which is to be secured. The mandrel D, with 20 its attached tube D', is inserted through the entire length of the tube B. The mandrel is turned by operating on the projecting end of the tube D'. The open end of the tube D' is engaged by a ratchet-lever, E, with the accompanying ratchet mechanism of the ordinary character, including a pawl, E', which engages with a toothed wheel, D², fixed on the tube D'. The attendant grasps the ratchet-lever E and vibrates it, with the effect of 25 revolving the tube D' and consequently the mandrel D, turning the screw G freely in its bearings in the cross-piece H.

The operation of the Dudgeon expander requires that the mandrel D shall be turned 30 strongly around either continuously or intermittently, and also that it shall be moved gradually endwise, so as to present a thicker and thicker portion of the mandrel to force the rollers outward. I effect and control the end 35 movement by a screw, G, and hand-wheel G'. The screw is marked G, and is tapped through a screw-plug, D³, strongly secured to the end of the tube D' by being tapped into the hub of the wheel D², which, as set forth hereinbefore, is fixed upon the tube end. A hand-wheel, G', is fixed on the end of the screw G. The latter is supported in a bearing, G³, between collars on the shank of the screw, as represented. The bearing G³ is supported in 40 a cross-piece, H, which is connected by tie-rods H' H' with a cross-frame, H², which latter applies closely around the tube D' and is maintained in position thereby. From the outer ends of the cross-frame H² are extended 45 rigid tubes H³, which connect to a yoke, H⁴, formed as shown, which abuts against the adjacent end of the ring C and gages the position in which the several parts of the expander 50 shall be held.

I is a tube mounted concentrically around the mandrel D and tube D'. It is supported and fastened at one end in the cross-framing H². On its other end is fixed a ring, I', of slightly larger diameter, in which are tapped 55 screw-pins i, the points of which engage with a ring, J, which is made in two or more pieces, and fitted with proper lubrication in a

groove in the boss or neck K' of the housing K, which latter forms the main supporting-frame of the expander.

The ring J in the groove in neck K' of the housing affords an extending bearing, so that the housing will be connected most strongly and firmly to the tube I, while tube and housing are free to rotate independently of each other—that is, the connecting, as set forth, fastens the housing and tube together, so that they must move together longitudinally, but are free to rotate independently.

I believe it practicable to employ the ordinary Dudgeon expander, with rollers of proper size and form to accomplish the desired end, the rollers being of such size and so mounted, as usual, that the mandrel D will act directly against each other, forcing it outward to perform its portion of the required expanding of the tube. While the narrow surface on each roller which I propose to present against the interior of the tube is ample for the distension of the tube, it is liable to cut and abrade 85 the mandrel D by reason of concentrating the pressure on a narrow portion of the surface. I avoid this by using a double set of rollers. The outermost rollers are marked M. They are six in number, and are each formed with 90 a bead or narrow swelled surface on its exterior and at about the mid-length. Each bears on two of the inner rollers, N, each formed with a large bearing-surface properly conditioned to rest fairly against the tapering mandrel, 95 and with a groove, n, equal to or a little greater than the bead m in each roller M. Each of the rollers M and N is formed with a trunnion at each end. On each trunnion are fitted two links, P P. These links unite the 100 several rollers and compel them to serve as a united system, but without interfering with the expansion of the work by changes of position of the rollers as the mandrel is driven in.

The two parts of the housing K are connected by thimbles K² and bolts K³, as is plainly shown in Figs. 1, 4, and 5.

The ring C is tightly and permanently set on one end of each length of tube. This may be done in the factory before the tubes are 115 brought into position for joining them to form a continuous line. In operating to attain this latter end each tube is brought into position and inserted to the proper extent into the ring C, which has been attached to the previous length and now forms a part of the line of pipe. The yoke H and its several attachments, if not previously put in place on the tube, are now applied, and all the parts being 120 in the position shown in Fig. 1, the hand-wheel G' is turned to drive the mandrel D endwise sufficiently to bring the rollers M N to their bearings against each other and against the interior of the tube B. Now, the lever E is reciprocated actively and the hand-wheel G' turned gradually, with the effect to 125 turn the mandrel D intermittently around, and also to move it gradually endwise, forcing the innermost rollers, N, outward, and conse-
